Noah S. Amstutz Inventor

UNITED STATES PATENT OFFICE

NOAH S. AMSTUTZ, OF VALPARAISO, INDIANA

AUTOMATIC ENGRAVING

Application filed July 28, 1928. Serial No. 296,075.

My invention relates to improvements in automatic engraving and it more especially consists of the features pointed out in the annexed claims.

5 The purpose of my invention is to provide a process and means for automatically producing engraving for surface or intaglio printing without the intervention of so-called half-tone screens; that employs for relief 10 printing purposes a negative carbon relief photograph; that utilizes a positive carbon relief photograph for the ultimate production of intaglio prints; that additionally employs a reversal step in changing an ordinary 15 kodak film from a negative to a positive for use in producing a carbon relief photographic negative and from this an engraved film for direct relief printing; that maintains a close mathematical relation between the included V angle of the graving tool, the maximum 20 relief of the photograph and the cooperating lines per inch of the engraved result; and that makes use of a cold dry-mat duplicating step for stereotyping the engraved result and subsequently printing it on soft 25 paper by rapid rotary presses.

With these and other ends in view I illustrate in the accompanying drawing such instances of adaptation as will disclose the 30 broad underlying features of my invention without limiting myself to the specific details shown thereon and described herein.

Figure 1 is a diagram of an ordinary negative.

35 Fig. 2 is a diagram of the first stage of a reversal of Fig. 1.

Fig. 3 is also a diagram of the second stage or complete reversal of Fig. 1.

40 Fig. 4 is a diagram of a positive being printed onto a paper supported carbon tissue.

Fig. 5 is a similar diagram to Fig. 4. The positive however being jointed onto a carbon coating on a transparent base.

45 Fig. 6 shows a diagrammatic representation of a carbon relief print secured by the means shown in Figures 4 or 5.

Fig. 7 is an enlarged diagram of an engraved film superposed on a carbon relief photo.

50 Fig. 8 is a detached diagram showing the

relation of relief, lines per inch and angle of graver.

Fig. 9 is also a diagrammatic view showing a dry-mat impression under rolling pressure.

Fig. 10 is a diagram of a "mat" being "cast" with type metal in stereotyping.

In a general sense the engraving technique described in the Patent No. 569,595, granted on Oct. 13, 1896, and the patent issued on Nov. 24, 1903, bearing number 744,852 is used in producing the engravings described herein. One of the outstanding shortcomings of the process and method disclosed in these patents is the fact that hitherto it has been impossible to use film engravings 10 formed on celluloid for printing purposes with hot stereotyping which has been universally in vogue. The reason for this difficulty is found in the fact that the wet papier-mâché flong after being beaten into the form was heated to dry it while in situ, thus destroying the celluloid film. To first electrotypes the film involved inadmissible delays. Now as the dry-mat stereotype 15 has come into practical use it is possible to simply place an engraved celluloid film 10 onto a suitable base 16 which with the thickness of the film is not more than type-high (.918") and lock it in the form with linotype slugs, display-type, etc.

Another difficulty encountered heretofore in producing such films for relief printing has been the necessity of changing an ordinary negative 1 into a lantern-slide transparency or positive and using this for producing a carbon relief negative 8 to be the original from which the engraved film 10 is made. This involved considerable time which is now obviated through the use of a negative reversal step (Figs. 1 to 3 inclusive) 85 similar to that employed in natural color photography and the use of dry-mat stereotyping. In this way a new result—the final printing stereotypes 18 are secured.

In practicing my invention, I may use such 95 alternative expedients and equivalents as the exigencies of varying conditions may demand, without departing from the broad spirit of the invention.

The successive steps from the beginning 10

to the end are outlined in the following description. An ordinary kodak or other negative 1, Fig. 1, is developed at 2 in any well known manner by metol-quinol, rodinal, etc.

5 At the conclusion of the development the film or plate is rinsed for about twenty seconds and is then placed in any suitable reversing bath, such for instance, as

10 Permanganate of potassium 2 grams — 31 grains
Sulphuric acid 10 ccs. — 170 minims
Distilled water to 1000 ccs. — 35 oz.

After leaving the plate or film in this bath for two or three minutes it should be examined under a weak white light. When all 15 the developed or metallic silver 2 of the original exposure has disappeared the film is washed for about a minute. After the primary image 2 is completely dissolved and the plate well washed the emulsion side 3 20 is exposed to white light and redeveloped at 4 by the original developer or by means of the following: Anhydrous sodium sulphate 15 grams (135 grains), Amidol 5 grams (45 grains), and distilled water to 1000 cubic centimeters (35 ounces). When this second 25 development has completely changed the silver bromide 4 by reduction, the plate is washed for three or four minutes and allowed to dry.

30 The positive 5 so produced (Fig. 4) is then placed on a piece of sensitized carbon tissue in which a small amount of pigment has been incorporated with the gelatine coating 6 on the paper supporting sheet 23 during the 35 process of manufacture, exposed to an enclosed 110 volt arc lamp, consuming about ten amperes of current at a distance of ten inches for a period of ten minutes. The tissue 6 is sensitized by means of two per cent 40 bichromate of potassium, and a safe edge is used as with ordinary autotype carbon tissue. The print is developed in water of about 110° F. Before the development it is squeegeed face down onto a piece of thin 45 celluloid as a support during the development, the paper backing 23 removed and the unacted gelatine 22 washed off. As soon as dry the negative relief print 8 is placed on the drum 12 of the engraving machine, 50 underneath a piece 10 of transparent or other celluloid about .005 inch thick. To avoid the use of the paper support 23 the gelatine 8 may be applied to a thin transparent celluloid 7 which is printed with the celluloid 55 face against the transparency so that the subsequent development with hot water to remove the soft gelatine 22 and retain the hardened portions 21 will commence immediately without the necessity of stripping off 60 a paper support 23 as is common in the use of carbon tissue.

In the production of such gelatine relief prints 9 it is impossible to always secure the same maximum height of relief 19 hence the 65 engraving steps must compensate for this

variation by coordinating the lines per inch l with the included angle a of the V shaped graving tool or incisor 11. This relation is shown on Fig. 8. If the tool or graver angle a remains constant then the lines per inch l must vary with changes in the extent of the relief r . Should the lines per inch l remain constant, at a given number, then the angle a of the graver must change accordingly. In practice it is simpler to retain an average graver angle a for a given kind of results, depending on the kind of paper, etc. to be used in printing, and change the lines per inch l by means of change gears, such as are well known in cutting screw threads on a lathe.

The drum or cylinder 12 of the phonograph-like engraving machine is rotated at about 120 revolutions per minute. Paradoxically as it may seem the sharp point of the graver 11 pushes the superposed celluloid sheet 10 away from in front of itself into the hollows 20 of the carbon relief 8. To assist in this a sapphire presser foot (not shown) located adjacent the graver overcomes variations in the surface tension of the celluloid film on which the engraving 10 is being made.

The mechanism has been christened an Akrograph; relief printing results, Akrotones; and intaglio printing results, Akrogravures.

When stereotyping steps are not encountered these engraved films 10 can be cemented to a wood base 16 and printed from direct. In fact, for some time it has been held that the theoretical so-called "cold stereotype" could be used, but it has not, until relatively recently been possible to procure the dry-mats for stereotyping as they have not been in practical use. These dry-mats 15 are now available for distribution through the mails, thus eliminating the heavy transportation charges incurred prior to their use when "boiler-plate" was sent from metropolitan centers to the smaller dailies, etc., located in the country where metal duplicates of such mats are made to be placed in the forms for subsequent restereotyping.

The dry mats 15 are produced on a press provided with a roller 13 and a horizontally movable bed 17. The engraved film 10 is placed on any suitable base 16, the mat is then laid on top and it is covered by a rubber blanket 14 which presses the dry papier-mâché into the wide and deep grooves 24 and the narrow and shallow grooves 25 thus completing the mat 15 which may be subsequently placed in the usual casting box (not shown) and hot type metal forced against it to form a stereotype 18.

A single engraved film 10 when placed on a suitable base has impressed thereon a dry relatively cold mat from which an individual mat may be produced to form a matrix for 130

subsequent stereotyping. In ordinary practice the film 10 is held on a base 16, against side slipping, by a trace of thin honey, or otherwise. It is made a part of the regular form associated with linotype slugs, display-type, etc., etc., the whole being held in a chase as usual. On such a form the dry mat is placed to cover its entire surface and the whole is subjected to pressure. After the 5 form and mat have passed under the pressure roller, the impressed mat is removed leaving the engraved film 10 on its base in the same condition as when it was assembled with the other matter. The impressed mat, opposite 10 any wide open spaces, is then backed up with gummed strips of considerable thickness so as to produce greater depth in the metal cast, wherever these open spaces occur. The mat 15 so treated is afterward subjected to moderate 20 heat to remove any moisture present in the adhering strips and it is then placed in a curved mold of substantially the same diameter as the printing cylinder. Melted type metal is then poured against the mat, to 25 produce the printing face of the entire form locked up in the chase. The term, "relatively cold mat" is understood to mean such a temperature as will not destroy the incision of the engraved film.

30 What I claim is:

1. In an automatic engraving process in which a carbon relief is produced with varying heights corresponding to gradations of light and shade over which a film of celluloid 35 is placed and both are held in contact with each other on a suitable support and while so held incisions of variable depth and width corresponding to the varying heights of the relief are made in the film as the relief and 40 the superimposed film are moved adjacent the incisor, which method consists in pressing a relatively cold dry mat into the incisions, and in subsequently depositing metal against the reversed incisions of the mat to 45 form a surface for relief printing.

2. In an automatic engraving process for relief printing in which a photographic negative is reversed into a positive and a variable height carbon relief is produced from the 50 positive over which a film of celluloid is placed and both are held in contact with each other on a suitable support and while so held incisions are made of varying depth and width in the superposed film according to the 55 variations in height of the carbon relief through a movement between the support and the incisor, which method consists in pressing a cold dry mat into the incisions, and in depositing metal against the reversed incisions 60 produced in the mat to form a printing surface.

In testimony whereof I affix my signature.
NOAH S. AMSTUTZ.
